UNITED STATES PATENT OFFICE.

WALLACE E. WARD, OF ROCHESTER, NEW YORK, ASSIGNOR TO ARTHUR H. INGLE, OF ROCHESTER, NEW YORK.

VERTICAL LATHE.

Application filed May 18, 1920. Serial No. 382,332.

To all whom it may concern:

Be it known that I, WALLACE E. WARD, a citizen of the United States, and resident of Rochester, county of Monroe, State of New York, have invented an Improvement in Vertical Lathes, of which the following description, in connection with the accompanying drawings, is a specification, like characters on the drawings representing like parts in each of the several views.

This invention relates to metal working lathes and more particularly to an improved type of lathe wherein the ways on which the tool saddles are mounted extend vertically, with the operating connections and gearing for effecting changes of feed and changes of speeds housed in the base of the machine. One principal object of the invention is to provide improved means for mounting, and controlling the movements of the tool saddle and tool holder with relation to an operating screw therefor, whereby either a vertical feed or a horizontal cross feed or a taper, or pattern-controlled feed may be obtained at will, with a capability of changing the setting of a machine for any required purpose in a quick and convenient manner. To these ends one important structural feature of invention consists in arranging the feed screw so that it may be held from endwise movement in a fixed swivel to feed the tool saddle, or it may be arranged so that the screw moves endwise in a relatively fixed nut according to the requirements of the work in hand. The foregoing and other objects and advantages of the invention will more fully appear from the following detailed description, and the distinctive features of novelty will be thereafter pointed out in the appended claims.

Referring to the drawings:

Fig. 1 is a front view of a vertical lathe embodying the invention;

Fig. 1^a is a fragmentary elevation and section of a feed screw;

Fig. 2 is a side view thereof partly in vertical section and looking from the right in Fig. 1;

Fig. 3 is a plan view of the machine with portions broken away in section;

Fig. 4 is a partial vertical section on line 4-4 of Fig. 1;

Fig. 5 is a partial horizontal section on line 5-5 of Fig. 1;

Fig. 6 is a fragmentary elevation showing a device for holding a controlling clutch in adjusted position; and

Fig. 7 is a detail transverse section on line 7-7 of Fig. 6.

The base 1 of the machine constitutes a housing for the change speed and change feed connections to be described and has fitted at the rear thereof an upright structure 2 at the front of which are formed spaced apart slide-ways 3, 4 for the tool saddles. Horizontally journaled in the base of the machine is a shaft 5 which may be considered the prime drive shaft of the machine, having as shown a projecting end to which is fixed a bevelled gear 6 meshing with a bevelled pinion 7 on a shaft 8 which may be a power distributing shaft from the motor unit and adapted to drive one or more machines that may be geared thereto. The shaft 5 has slidably keyed thereon a pinion block 9 bearing pinion faces 9^a, 9^b, 9^c of diverse sizes with the intermediate one thereof the largest. This pinion block is engaged by a suitable shifter 10 for actuation to its adjusted positions. A shaft 11 is journaled in the base in parallelism with the shaft 5 and adjacent thereto and has keyed thereon spaced apart gears 12, 13, 14 adapted to mesh with the pinion faces 9^a, 9^b, 9^c respectively as the pinion block is shifted to its several positions of adjustment. The shaft 11 has fixed to the inner end thereof a bevelled pinion 15 which drives a bevelled gear 16 keyed to the spindle 17. The work spindle 17 is vertically journaled in the base with its upper extremity 17^a projecting thereabove and adapted to receive a face plate or work holding chuck. Thus by the shifting of the pinion block 9 three changes of speed to the spindle may be obtained.

The shaft 11 has detachably keyed to its outer projecting end a pinion 18 engaging a gear 19 detachably keyed to the end of the shaft 20 journaled in the base. The pinion 18 and gear 19 are removable and replaceable by others of different relative sizes whereby a change of speed ratio from the shaft 11 to shaft 20 may be obtained as desired. This connection to the shaft 20 is

for the transmission of feed movement to the tools and the shaft 20 has keyed thereon a pinion 21 which meshes with gears 22, 23 loosely mounted on shafts 24, 25 respectively 5 journaled in the base at each side of the shaft 20. Each of the shafts 24, 25 has slidably keyed thereon a double ended clutch hub 26 which when moved in one direction engages a cooperative clutch face on the hub 10 of the gears 24, 25 to engage them with the shafts on which they are mounted. Each of the shafts 24, 25 has fixed at its inner end a bevelled pinion 27 engaging a pinion 28 having a hub 28^a swiveled in the base and 15 having a passage therethrough in which is slidably keyed a plain shaft portion 29^a depending from a screw 29 which extends vertically. The screws 29 extend upward in proximity to the respective saddle ways 3, 4 20 and since these screws and the saddle mechanism associated therewith are shown as similar, only one of them need be further explained. The pinion 28 is also shown as engaged by another bevelled pinion 30 fixed at 25 the inner end of a shaft 31 horizontally journaled in the base and equipped with a squared projecting end 31^a adapted for engagement with a wrench or like hand operating device. The shafts 24, 25 also have 30 loosely journaled thereon adjacent the outer ends thereof gears 32 which are engaged with the gear 12 on the shaft 11 and constantly driven thereby. These gears have hubs 32^a thereof formed with clutch faces 35 engageable by the other ends of the clutch hubs 26. Thus by shifting these clutch hubs to make fast the gears 32 to their shafts, power may be transmitted directly from the gear 12 to the respective shafts, 24, 25, this 40 transmission being for the rapid traverse movement. For controlling the position and movements of the clutch hubs 26 each of them is engaged by a shifter 33 fixed on a slide rod 34 fitted in the base. This rod is 45 normally held yieldingly in an intermediate position with the clutch hub disengaged at both ends by springs 35 engaging collars 35^a on said rod. The rods 34 may be shifted to engage the respective clutch hubs 26 for 50 either rapid traverse movement or feed movement by suitable manually operated shifters, these being shown as lever arms 36 pivoted to the housing at 37 and having horizontally extending lever handles 38 which 55 project from the housing. Suitable means is provided for holding the clutch hubs in either operative position until tripped by the tool holder movement, such means, as shown, comprising notches 39 in the top 60 of the rods which are engaged by dogs automatically controlled by the tool holders as more fully explained later herein.

Each of the respective vertical slideways 3, 4 has slidably fitted thereon a saddle 40 equipped with a nut 41 engaging the screw

29. This saddle while adapted for free sliding movement along its slide-way is equipped with provision for rigid and stationary clamping to such slide-way to permit the functioning of the mechanism in one of the 70 ways of which it is capable as later explained, and for this purpose the saddle is equipped with clamping screws 42 engaging a clamping shim 43 and having operating handles 44 for setting up such screws. The 75 face of the saddle 40 is formed with a usual undercut ring slot 45 in which are engaged the T-headed clamping bolts 45^a which secure a swivel head 46 thereto in any position of angular adjustment. The swivel head 46 has slidably fitted thereto a tool holder 47 which as usual engages undercut ways of the swivel head. The tool holder is adjustable with reference to the saddle and its swivel plate by means of a screw 48 engaging a nut 49 of the tool holder, this screw being swiveled in a sleeve head 50. The sleeve head 50 is borne by a slide block 51 which has dove-tailed sliding engagement with a rail 52 equipped for this purpose with undercut ways. The rail 52 is pivoted by a pin 53 to a plate 54 which is borne by, and depends from, a bracket head 55. The plate 54 is formed with upper and lower arcuate slots 56, 57 in which clamp bolts 58 are engaged to clamp the end portions of the rail 52 immovably to said plate in any position of angular adjustment to which such rail may be set. The bracket head 55 is slidably fitted to a vertical way 3—4 of 100 the lathe and it is adapted to be clamped immovably thereto when desired by clamp bolts 59. The bracket head 55 has swiveled therein the upper end of the feed screw which is thus held from endwise movement 105 with respect thereto as indicated at 60. Suitable means may be provided for counter-balancing head 55 and the saddle, this being shown as a usual cable or chain 61 passing over a plate 62 at the top of the upright and 110 holding a counter weight 63. With the described construction it may now be understood that when the lathe is to be used for vertical turning, the head 55 will be clamped rigid to the upright by the clamp screws 59 115 and the rail 52 set vertical, i. e., in parallelism with the saddle ways, whereupon on actuation of the screw 29 the tool holder borne by the saddle will move vertically, the saddle being then released for free movement along its ways. For turning tapered work the rail 52 may be set at any required angle by adjusting the clamp bolts 58 in the slots 56, 57 which will cause the tool holder 120 to move horizontally on the swivel plate 46 as the saddle bearing the tool holder moves vertically. For turning horizontal work the saddle 40 is clamped immovably to its ways by the clamp screws 42 and the head 55 is released to slide freely on the vertical ways. 125

Then on setting the rail 52 at a suitable angle, the head 55 will be moved vertically with the screw 29 which operates through the then stationary nut 41 and this movement will cause a transverse movement of the tool holder on the saddle so that the tool may thus be fed horizontally over the work surface. It will be understood that swivel head 46 may be set as usual at the proper angle so that the tool will be presented squarely to the work in whichever direction it may be fed, the swivel connection of the sleeve 50 with the block 51 indicated at 50^a permitting this adjustment without disturbing the relation of the tool holder to the rail 52.

The notches 39, already referred to, are engaged by oppositely facing dogs 64, 65 pivotally mounted on the same pivot pin 66, 20 borne by the housing and adapted to engage oppositely facing shoulders 39^a, 39^b respectively of the notches and they are spring pressed to snap into these notches when permitted, by a coil spring 67 mounted on the pin 66 and having its ends engaging the respective dogs. These dogs have tail pieces 64^a, 65^a respectively which are engaged by down-turned ends of a tilting plate 670 also pivotally mounted on the pin 66. The plate 30 670 is pivotally engaged as indicated at 68 near the right hand end thereof as shown in Figs. 2 and 6 by the vertically extending rod 69 which is slidably guided upward alongside the vertical way, it being understood 35 that there is one of these rods with the described cooperative mechanism associated with each of the slide rods 34 for each of the saddle and tool head mechanisms. The rod 69 is equipped with spaced apart collars 40 70 adjustably fixed thereon and adapted to be impinged by the saddle or by the head 55 according to which of these is movable, to move the rod 69 and hence cause the plate 67 to press one or the other of the dogs 64, 45 65 out of its notch according to whether the connection has been set for the rapid traverse or for the feed. Thus if the hub 26 has been set for rapid traverse, upon the end of the rapid traverse movement, the rod 69 will 50 be lifted and the dog 64 raised to permit the clutch hub to move back to neutral position, while if the feed connection has been engaged by the shifting of the clutch hub to the left in Figs. 2 and 4, upon the completion 55 of the feed movement the rod 69 will be moved downward disengaging the dog 65 from its notch and again permitting the clutch hub to move to neutral position. It will be understood that while I herein show 60 the tool saddles and associated mechanism as the same on the two vertical ways, this is merely illustrative in certain broader aspects of the invention and tool mountings of different character one from another may be employed on the respective upright ways if 65

desired. In general the present invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent is:

1. A lathe comprising a work spindle, a slide-away, a feed screw equipped with driving means and having a mounting permitting endwise movement thereof with respect to such driving means, a saddle mounted for movement on said slide-way bearing a slideable tool holder and equipped with a nut engaging said screw, and a head also fitted to said slide-way in swiveled engagement with said screw and bearing means for effecting a sliding movement of said tool holder, said saddle and said head equipped with means for selectively clamping them stationary with respect to said slide-way.

2. A lathe comprising a work spindle, a saddle bearing a tool holder slidably thereon mounted for movement with respect to said spindle, a head bearing an angularly adjustable rail slidably engaged by said tool holder also movably mounted with respect to said work spindle, and means for holding either said saddle or said head stationary while the other remains movable for the purpose stated.

3. A lathe comprising a work spindle, a slide-way, a screw having change feed connections with said spindle, a saddle bearing a slideable tool holder fitted to said slide-way and operatively engaged by said screw, and a head also fitted to said slide-way and held to move endwise with the screw, said head bearing an angularly adjustable member slidably engaged by said tool holder and said saddle and said head each equipped with means for holding it stationary while the other thereof is movable.

4. A lathe comprising a work spindle, a feed screw having change feed gear connections with said spindle and mounted for endwise sliding movement therethrough, a saddle bearing a movable tool holder engaged with said screw, a head swiveled to said screw and bearing means for moving said tool holder upon relative movement between said saddle and head, and means for holding said saddle or said head stationary selectively in operation.

5. A lathe comprising a work spindle, a slide-way, a feed screw in geared connection with said spindle and mounted for endwise sliding movement, a saddle engaged with said screw and bearing a slideable tool holder,

- 41
- a head swiveled to an end of said screw bearing a depending projection equipped with an angularly adjustable rail with which said tool holder is slidably engaged to produce movement thereof upon relative movement between said saddle and said head, and means for selectively clamping said saddle or said head stationary while the other is movable for the purpose stated. 50
- 10 6. A lathe comprising a work spindle, a saddle bearing a tool holder slidably fitted thereon, a feed screw in geared connection with said spindle and mounted for endwise movement with respect thereto, and means 55 operated by said screw for moving said tool holder either axially or transversely with respect to the spindle axis. 60
- 15 7. A lathe comprising a work spindle, a saddle bearing a tool holder slidably thereon, a feed screw mounted for endwise movement and equipped with means for holding it from such endwise movement at will, and means operated by said feed screw for moving the tool holder either axially or transversely of the spindle axis or in a direction inclined thereto at will. 65
- 20 8. A lathe comprising a work spindle, a tool holder, a feed screw having connections for rotation and mounted also for endwise movement with means for holding it against such endwise movement at will, and means 70 operated by said screw for moving the tool holder either endwise of the spindle axis when the screw is held from endwise movement, or transversely when the screw is permitted to move endwise. 75
- 25 9. A lathe comprising a work spindle, a tool holder, a feed screw having connections for rotation and mounted also for endwise movement with means for holding it against such endwise movement at will, and means 80 operated by such screw for moving the tool holder either endwise of the spindle axis when the screw is held from endwise movement, or transversely when the screw is permitted to move endwise, said means embodying an angularly adjustable rail engaging the tool holder and permitting the tool holder to be moved also in a direction inclined to the spindle axis at will. 85
- 30 10. A vertical lathe comprising a base housing, an upright work spindle journaled therein, a plurality of vertical slide-ways extending upward from said base each equipped with a saddle, feed screws engaged with said saddles, change feed and rapid traverse connections to said screws housed in said base and equipped with means for selective engagement with the respective screws to impart either a relatively slow feed movement in one direction or a rapid traverse movement in the other direction thereto at will. 90
- 35 11. A vertical lathe comprising an upright work spindle, a base housing in which said spindle is journaled, a plurality of upright slide-ways extending from said base each bearing a saddle and a slideable head apart from said saddle, feed screws for the respective saddles having change feed and rapid traverse connections in said base, said screws mounted for rotation and also for endwise sliding movement at will, said saddles and said heads equipped with cooperative means for causing the tool holders on said saddles to move endwise of the spindle axis or transversely thereof at will. 95
- 40 12. A vertical lathe comprising an upright spindle, a base housing, a plurality of slide-ways extending upward from said housing, each equipped with a saddle bearing a tool holder, operating screws for said saddles, change feed and rapid traverse connections for said screws housed in said base, and equipped with clutch connections for selective engagement with said screws, and automatic means for disengaging any one of said clutch connections after predetermined movement of a saddle on either its rapid traverse or its feed movement. 100
- 45 In testimony whereof I have signed my name to this specification. 105

WALLACE E. WARD.
